[57] CLAIM

The ornamental design for a holder for sheet material, as shown and described.

DESCRIPTION

FIG. 1 is a front elevational view of a new holder for sheet material showing my new design;

FIG. 2 is a bottom plan view;

FIG. 3 is a rear elevational view;

FIG. 4 is a top plan view;

FIG. 5 is a right end elevational view, the opposite end being a mirror image thereof.

FIG. 6 is a front elevational view of a second embodiment of my new design;

FIG. 7 is a right end elevational view of FIG. 6, the opposite end being a mirror image thereof;

FIG. 8 is a bottom plan view of FIG. 6;

FIG. 9 is a rear elevational view of FIG. 6;

FIG. 10 is a top plan view of FIG. 6;

FIG. 11 is a left front perspective view of FIG. 1 on an enlarged scale; and

FIG. 12 is a left rear perspective view of FIG. 1 on an enlarged scale.

FIG. 1.

FIG. 2.

FIG. 3.

FIG. 4.

FIG. 5.

FIG. 6.

FIG. 8.

FIG. 9.

FIG. 10.

FIG. 11.

FIG. 12.
